UNITED STATES PATENT OFFICE.

VICTORIA E. LAVALLIE, OF ST. ALBANS, VERMONT.

SHIRT OR DRESS PLACKET.

SPECIFICATION forming part of Letters Patent No. 330,498, dated November 17, 1885.

Application filed March 20, 1885. Serial No. 159,577. (No model.)

To all whom it may concern:

Be it known that I, VICTORIA E. LAVALLIE, a citizen of the United States, residing at St. Albans, in the county of Franklin and State of Vermont, have invented certain new and useful Improvements in Shirt,&c., Plackets; and I do declare the following to be a full, clear, and exact description of the invention, such as will enable others skilled in the art to 5 to which it appertains to make and use the same, reference being had to the accompanying drawings, and to the letters and figures of reference marked thereon, which form a part of this specification.

15 The object of my invention is to provide a placket for the slit-openings of shirts, overalls, &c., one made from a single piece of cloth and having when attached, no seam at the edge of the facing, but presenting an edge of 20 solid cloth, whether the tearing strain comes from the right or left, the bottom of the placket being also of whole cloth. A further object is to do away with the objectionable thicknesses of cloth usual to devices of this kind, 25 and to have the outer facing of the placket lap well over the inner, giving a finished appearance and dispensing with the second button.

My invention consists in a peculiar method 30 of attaching the placket-blank, shaped as shown, to the slit-opening of a shirt or suitable garment, whereby a placket is produced whose bottom and tearing edges are of whole, folded, and seamless cloth, and whose outer 35 facing laps by the inner sufficiently to ordinarily conceal it and dispense with a second button.

In the drawings, Figure 1 is a plan view of 40 the placket-blank. Fig. 2 is a plan view showing the manner of attaching the long side of the placket-blank. Fig. 3 is a plan view showing the larger portion of the placket-blank ready to be turned over to form the outer facing and shield, the inner facing being 45 turned under. Fig. 4 is a front elevation showing the appearance of the placket when the slit-opening is closed. Fig. 5 is a perspective view showing the placket partly open.

50 Like letters refer to like parts.
Referring to the blank, (see Fig. 1,) it will

be seen that it is a single piece of cloth. The larger or rectangular portion A forms the outer facing, and terminates in the somewhat pointed and narrower portion B, which forms 55 the outer shield, and the still narrower portion or strip C, which forms the inner face of the placket.

Besides the advantage of making a placket of whole cloth, it will be evident that my blank 60 can often be cut from waste cloth.

I do not limit myself to the exact form of the blank shown, and propose to use any fair equivalent.

The said blank is applied to form a placket 65 as follows: If it is to be applied to a shirt-opening, for instance, spread out the slit until edges of the cloth body form a straight line, (see Fig. 2,) and place underneath the blank so that the edge of the long side of it 70 shall lie under the edge of the cloth body, then fasten the parts together by a single seam about one-fourth of an inch from the edges. Now spread out the cloth body and the blank flat, turn over the free edge of the narrow strip C about one-fourth of an inch and lap the whole onto the cloth body, single-seaming it to place, thus forming the narrow or inner face of the placket, said face being from 75 one-half to five-eighths of an inch wide, or as 80 the case may be. The inner facing being completed, turn it back to its natural place under the portion A of the blank. (See Fig. 3.) Now turn over the free edge of the portions A and B of the blank, say, one-fourth of an inch, and 85 lap the whole over onto the cloth body, fastening to place by double-stitching down and around to the bottom of the placket, and then horizontally across, thus forming the outer 90 facing and the shield below. (See Fig. 4.) Preferably, the portion A of the blank should 95 be of such width that when the placket is put on, the outer facing will form an extension to the portion D of the cloth body of about one inch, thus giving this extension but two thicknesses of cloth only, and allowing it to lap beyond the inner facing about one-half of an inch when the placket is closed, the overlap giving the whole a neat appearance and dispensing with the second button. It will be noticed 100 that there are no seams at the tearing-edges of the placket, and said edges being formed

by folding the blank, they will resist strain from any direction, as they present the resistance of whole cloth.

My placket is simple and strong, and presents a finished look, whether from the inside or outside, and the seams are so arranged as to give the least thickness of cloth.

Having fully described my invention, what I claim, and desire to secure by Letters Patent,
10 is—

The method of attaching to a shirt-opening a placket-blank comprising the portions A, B, and C, which consists, first, in single-seaming the long side of the blank to the slit
15 opening, then folding over and stitching to the cloth body the portion C, to form the nar-

row inner facing, next folding over and double-stitching to the cloth body the portions A and B, to form the wide outer facing and a shield below, whereby a placket is produced 20 whose bottom and tearing edges are of whole, folded, and seamless cloth, and whose outer facing laps by the inner sufficiently to ordinarily conceal it and dispense with the second button, substantially as set forth. 25

In testimony whereof I affix my signature in presence of two witnesses.

VICTORIA E. LAVALLIE.
